GOLF BAG

Filed Aug. 13, 1927

G. A. Howe
INVENTOR
BY Victor J. Evans

ATTORNEY

UNITED STATES PATENT OFFICE

GLENN ARNOLD HOWE, OF SILVERTON, OREGON

GOLF BAG

Application filed August 13, 1927. Serial No. 212,718.

This invention relates to receptacles, and its general object is to provide a golf bag that will stand erect and be retained in such position for conveniently removing and replacing clubs and other articles therefrom and therein, as well as for other purposes, and said bag can be so positioned and removed therefrom in an easy and expeditious manner with very little effort.

10 Another object of the invention is to provide a golf bag including means for supporting the same in an upright position, that is simple in construction, inexpensive to manufacture, strong and durable and efficient in 15 operation and service.

This invention also consists in certain other features of construction and in the combination and arrangement of the several parts, to be hereinafter fully described, illustrated in 20 the accompanying drawings and specifically pointed out in the appended claim.

In describing my invention in detail, reference will be had to the accompanying drawings wherein like characters denote like or 25 corresponding parts throughout the several views, and in which:

Figure 1 is a front elevation of the golf bag forming the subject matter of the present invention with parts broken away and in 30 section.

Figure 2 is a top plan view showing parts in section.

Referring to the drawings in detail, the reference numeral 1 indicates the body of the bag 35 which is of the usual elongated cylindrical construction and has fixed thereto a handle 2 as well as a strap 3 in the usual manner. The body 1 is reinforced at its upper end by a beaded metallic collar 4 which is riveted or 40 otherwise secured thereto as shown. The bottom is indicated by the reference numeral 5 and includes the usual annular flange 6 secured to the body by rivets 7.

The bottom is provided with an opening 45 centrally disposed therein and secured about said opening through the medium of a flange 8 and rivets or the like as shown is a sleeve 9 which is provided with an enlarged cup shape lower portion 10. A plate 11 is fixed 50 to the lower side of the bottom and is pro-

vided with a centrally disposed opening aligned with the interior of the sleeve.

Secured centrally in the body through the instrumentality of radiating rod bolts 12 is a disk 13 having an annular flange depending 55 therefrom which threadedly receives the inner ends of the rod bolts while the outer ends of said rod bolts are fixed in the collar 4 as best shown in Figure 2 of the drawings.

The disk 13 is provided with a centrally 60 disposed opening through which passes a shaft 14 mounted for slidable movement therein, and said shaft extends through said body and the sleeve 9 as well as a felt washer 15 disposed in the cup shaped member 10. The 65 shaft further extends through the opening in the plate 11 and terminates in a pointed lower end 16. The rod bolts 12 are provided with spaced sleeves which have their ends engaging the flange of the disk 13 and the 70 inner side of the body as shown.

The shaft is provided with a handle 17 on its upper end so that it can be moved to either its operative or inoperative position as will be apparent, and when it is desired to support the bag in its upright or erect position as shown, the shaft 14 is disposed downwardly against the tension of a coil spring 18 and due to the engagement of the pointed end of the shaft in the ground or other place, it will 80 be obvious that the same will adequately retain the bag in its upright position. A slight pull upon the handle 17 will cause the spring to arrange the shaft to its inoperative position as will be apparent. 85

It is thought from the foregoing description that the advantages and novel features of my invention will be readily apparent.

I desire it to be understood that I may make changes in the construction and in the combination and arrangement of the several parts, provided that such changes fall within the scope of the appended claim. 90

What I claim is:

A golf bag of the character described comprising a body, a reinforcing collar for the top of said body, a bottom for said body and being provided with a centrally disposed opening arranged therein, a sleeve, a flanged cup shaped member formed with said sleeve 100

and being fixed to said bottom about said opening therein, a plate secured to the underside of said bottom and formed with an opening registering with the sleeve, a flanged disk having a central opening, rod bolts radiating from the flange of the disk and centrally securing the disk adjacent the upper end of said body to said reinforcing collar, a handled spring pressed shaft disposed in the opening of the disk, the sleeve and opening of the plate respectively, and terminating in a penetrating lower end, a felt washer disposed in said cup shaped member, and said shaft being mounted for slidable movement as and for the purpose specified.

15 In testimony whereof I affix my signature.
GLENN ARNOLD HOWE.
